UNITED STATES PATENT OFFICE.

LIZZIE TRANTHAM, OF MCKINNEY, TEXAS.

QUILTING-FRAME.

983,957.

Specification of Letters Patent. Patented Feb. 14, 1911.

Application filed December 24, 1909. Serial No. 534,776.

To all whom it may concern:

Be it known that I, LIZZIE TRANTHAM, a citizen of the United States of America, residing at McKinney, in the county of Collin and State of Texas, have invented certain new and useful Improvements in Quilting-Frames, of which the following is a specification, reference being had therein to the accompanying drawing.

10 This invention relates to quilting frames, and the principal object of the same is to provide a device of the character described that may be adjustably suspended from an overhead support and provided with raising 15 or lowering means, so that the frame may be suitably elevated to prevent the same interfering with the use of the room in which it is located, and also so that it may be adjusted relative to the floor to suit the convenience of the user. In connection with the 20 foregoing it is contemplated providing a simple type of frame the parts of which may be readily separated to minimize storage space, and which is provided with simple 25 means whereby it may be attached to the suspending means.

In carrying out the objects of the invention generally stated above, it will be understood, of course, that the essential features 30 of the same are necessarily susceptible of changes in details and structural arrangements, one preferred and practical embodiment of which is shown in the accompanying drawings, wherein:—

35 Figure 1 is a perspective view of the improved quilting frame and adjustable suspending means. Fig. 2 is a fragmentary plan view of the upper surface of one corner of the frame. Fig. 3 is a similar view of the 40 under surface of one corner of the frame. Fig. 4 is a horizontal sectional view of the windlass for adjusting the frame. Fig. 5 is a detail vertical sectional view of one of the hanger bearings for a single pulley. Fig. 6 45 is a similar view of one of the hangers for two of the pulleys.

Referring to the accompanying drawings by numerals, it will be seen that the improved quilting frame is composed of the 50 flat longitudinal members 1 and the similar transverse members 2 arranged with their ends in overlapping relation to provide a substantially rectangular frame to which the quilt 3 is laced in the usual manner. The 55 overlapped ends of the members of the frame are held in rigid, but separable re-

lation by the wires 4 that are looped around one of the members and passed over the other members in crossing relation and have their ends twisted together, as indicated at 60 5. The projected ends of the transverse members 2 have their longitudinal edges provided with oppositely disposed holding notches 6.

A supporting frame 7 is supported by a 65 wall or the like 8 said frame having a winding drum 9 therein that is rotated by the handle 10, and which is prevented from reverse movement by pawl 11 and ratchet 12. Four cables are connected with and adapted 70 to be wound upon said drum 9, said cables being designated by the numerals 13, 14, 15 and 16 respectively. Said cables are arranged in pairs, one pair for each end of the frame and extend from said drum 9 through 75 a guide opening 17 in the front of the frame 7. Cables 13—14 pass through a guide eye 18 in the ceiling 20 to and over the rollers 21—22 of hanger 23 secured to the ceiling. Cable 13 after passing over pulley 21 extends down to and is fastened to the rear notched end of one of the transverse members 2. Cable 14 after passing over pulley 22 extends to and over a pulley 24 mounted in a hanger bearing 25 and then extends 80 down to and is fastened to the forward notched end of the transverse end member to whose other end cable 13 is attached. Cables 15 and 16 pass through a guide eye 26 thence to and over pulleys 27—28 in a 85 hanger bearing 29, cable 15 after passing over pulley 27 extending down to and being fastened over the notched rear end of the transverse member 2 opposite to that to which cables 13—14 are fastened. Cable 16 90 after passing over pulley 28 extends to and over a pulley 30 in a hanger bearing 31 and then extends down to and is fastened to the notched forward end of the transverse member 2 to which cable 15 is fastened.

100 It will be seen that the four hanger bearings are arranged on the ceiling complementary to the four projected ends of the transverse members 2 so that their pulleys will permit the cables 13, 14, 15 and 16 to 105 depend vertically therefrom for connection with the said transverse members, thereby assuring of an even vertical adjustment of the frame by rotating the drum 9.

110 Another prominent feature of the invention is in the manner of connecting the members of the frame as it will be seen that they

are normally held in a rigidly relative position, but may be readily separated when necessary or desirable and also that the projected notched ends of the members 2 assures of the adjusting cables having a non-slipping engagement therewith.

What I claim as my invention is:—

The combination with a rectangular device, of separate suspension cables attached 10 to each corner of the device, a winding drum, guide means between said device and drum, said separate suspension cables each being of sufficient length to reach from its respective point of attachment to the device, 15 through said guide means, to the drum, each of said cables being independently attached

to the drum, whereby the angular position of the device may be varied, said cables when attached being adapted for simultaneously winding on the drum to lift the 20 device bodily and maintain the same in angular adjustment, rotating means for the drum, and releasable locking means for the drum.

In testimony whereof I hereunto affix my 25 signature in presence of two witnesses.

LIZZIE TRANTHAM.
